CLAIM

The ornamental design for a hand-held dispenser for stretch wrap film, as shown and described.

DESCRIPTION

FIG. 1 is a left side elevational view of a hand held dispenser for stretch wrap film, showing my new design the opposite side being a mirror image;

FIG. 2 is a rear elevational view;

FIG. 3 is a front elevational view;

FIG. 4 is a bottom plan view;

FIG. 5 is a top plan view; and

FIG. 6 is a cross sectional view of figure as taken from line 6—6 and FIG. 1.

FIG. 1

FIG. 2

FIG. 3

FIG. 4

FIG. 2

FIG. 5
